UNITED STATES PATENT OFFICE.

BURNHAM C. STICKNEY, OF RUTHERFORD, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed June 25, 1923. Serial No. 647,501.

To all whom it may concern:

Be it known that I, BURNHAM C. STICKNEY, a citizen of the United States, residing in Rutherford, in the county of Bergen and State of New Jersey, formerly of Elizabeth, New Jersey, have invented certain new and useful Improvements in Typewriting Machines, of which the following is a specification.

10 The invention relates to a machine for typing upon paper work-webs, comprising several plies, either fan-folded or unattached to each other, and upon each of which plies are usually printed a succession of forms; the form lengths or sections of one ply registering with those of the other plies, and carbons being interleaved with the plies.

The work-webs may be continuous, or of 20 indefinite length, according to the number of forms which compose the same. Ordinarily, however, or at least until so worn as to call for replacement, a fixed length of carbon-sheet is employed; the carbons 25 being shifted, relatively to the work-webs from one form-length to the next succeeding form-length of work-webs when the typing of a form is completed. The usual practice has been; after typing of a form, 30 first, to lift the platen bodily to release the web therefrom and to release the carbons for their shift; then to shift, one form-length rearward, a carbon-carrier with the carbons attached thereto, while holding the 35 work-webs; and then to reset the composite web for commencement of typing on the next form and to replace the platen.

In the co-pending application of Jesse A. B. Smith, Serial No. 640,315, filed May 21, 40 1923, there is described a machine, operating according to a somewhat different method, for obtaining the same results, and which has certain advantages as to lightness, simplicity and expeditiousness in its 45 manipulation. In this Smith machine, neither the platen nor a carbon-carrier need be shifted in the carbon-shifting operation. The carbons are anchored at their rear, and sufficient slack is provided the composite web between the platen and the anchorage 50 of the carbons to permit writing of a form before such slack is entirely taken up by the line-spacing movements of the platen. After completion of a form, the Smith procedure is: first, to reverse the platen until

the carbons are clear thereof and are loose in the work-webs; a slack in the carbons and work-webs being thus re-established between the platen and the carbon anchorage; then, to rock against the composite web an arcuate table to bend the web until the slack is removed; then, to rotate the platen to shift the work-web a form-length forward while the carbons are held stationary; and then, to return the rocking table to normal 65 position, re-establishing the slack; after which further forward rotary movement of the platen will serve to bring the composite web to position for typing on the fresh form-length, with the slack therein, originally provided. 70

The present invention relates more particularly to a machine of the general class of the aforesaid Smith machine, in that the platen need not be shifted as an incident to 75 the carbon-shifting operation, and in that means, such for instance as a rockable arcuate table, is employed to take up a slack in the web which is first established to permit line-space feed of the web without pull on 80 the carbon-carrier in the typing of a form, and which is re-established in the act of retracting the web to free the carbons from the platen preliminary to the form-to-form shift of the same relative to the work-webs. 85 The present invention, however, is primarily distinguished from the aforesaid Smith structure in that the carbon-carrier is not simply a stationary anchor for the carbons, but is movable to serve as the means by 90 which the form-to-form shift of the carbons is actually effected.

An object of the present invention is the provision of means whereby the carbon-carrier may be retracted (after elimination of 95 the aforesaid re-established slack in the web), to effect the form-to-form shift of the carbons along the web, thus rendering unnecessary forward advance of the web by rotation of the platen, or otherwise, for 100 effecting such form-to-form shift; and making possible a reduction of the required number of advances of the web, or platen, to the single advance involved in positioning the composite web for commencement 105 of typing on a form after the form-to-form shift of the carbons has been effected. In this connection, a feature of the invention is the avoidance 110 of the necessity for any gage to determine

by eye the correct amount of relative shift of the carbons and work-webs, such for instance as a gage to which the leading end of the work-webs has heretofore been fed by the platen; thus relieving the operator of considerable care.

A further feature of the invention is a mounting of the arcuate table, or equivalent device, and of the carbon-carrier, such that 10 the same may be supported independently of each other, and be movable independently of each other, in a manner best to co-ordinate their several actions on the web in a simple and compact structure.

15 A further feature of the invention is the provision of a novel and simple operating and locking means for a clamp device to hold the work-webs against displacement while the arcuate table, or its equivalent, 20 acts on the web to remove the slack re-established therein in freeing the carbons from the platen.

A further feature of the invention is the mounting of the arcuate table or equivalent device, between the platen and the carbon-carrier so that its further upward movement, after taking up slack in work-webs, will advance the paper from the rolls or folds, and its downward return will leave the slack in the work-webs in position between the carbon-carrier and the platen, ready for line-feed to the platen as the work proceeds.

Other features and advantages will hereinafter appear.

In the accompanying drawings.

Figure 1 is a view, in side elevation, of the platen-carriage and connected parts, embodying certain features of the present invention; the parts being in position for commencement of writing on a form.

Figure 2 is a view similar to Figure 1, with the additional showing of other parts, embodying features of the invention, the composite web being shown as fed rearward, after completion of typing on a form, to clear the carbons from the platen preliminary to the operation of effecting the form-to-form shift of the carbons relative to the work-plies.

Figure 3 is a view, in side elevation, of the apparatus shown in Figure 2; the web-supporting table being shown as lifted to take up the slack in the web after the web has been retracted to Figure 2 position.

Figure 4 is a view similar to Figure 3, except that the carbon-carrier has been thrown down to effect the form-to-form shift of the carbons relative to the work-webs.

Figure 5 is a top plan view of the apparatus shown in Figure 2.

Type-bars 10 strike against the front of a revoluble platen 11, which is journaled in the usual manner in a platen-frame comprising ends 12 and a rear paper-shelf 13. The usual releasable feed-rolls 14 run on the

under side of the platen. The platen-frame is mounted upon a carriage 15, for movement in letter-feed and return directions upon a rail 16. The platen may be rotated by knobs 17 on the axle 18 thereof, or by means 70 of the ordinary line-space mechanism, comprising a line-space wheel 20.

The work-web, usually comprising superposed plies 19 (which may be loose plies or which may be a fan-fold), is drawn up from 75 a supply-spool, or from a zigzag folded pile (not shown), but which may be contained in a receptacle arranged in the rear of the typewriting machine and its stand 21. As the plies of the work-web rise from the supply at 22, they first pass through a carbon-carrier. The carbon-carrier is in the form of a bail comprising arms 23, fast on a rock-shaft 24, journaled in plates 25 of a standard or frame, secured to a platen-carriage, and 80 movable with the latter in letter-feed and return directions. The plates 25, one at each side of the frame, are connected by a cross bar or tie 26, at the center of which there is an ear 27, having journaled thereon a roller 28 supporting the frame on a rail 29. The rail 29, along which the frame moves with the platen-carriage, is supported by brackets 31 on the rear of the machine-frame 32. Attachment of the carrier-frame to the platen-carriage is by means of ears 33, one formed on each of the side plates 25, and which are offset at 34, toward each other, to form flanges which are secured by screws 35 to brackets or arms 36, in turn, secured at 37 100 to the usual rear cross piece or tie 38, which forms part of the carriage 15.

The arms 23 of the carbon-carrier are connected at their distal ends by a cross-piece 39. At each end of the cross-piece is 105 a block 40; and secured to each of the blocks 40 is a carbon-carrier-blade 41. The blades 41 are shown as projecting from the blocks 40 between the plies of the work-webs; and the blocks 40 are either stepped or provided 110 with spacing-pieces, so that the blades may be suitably spaced apart for free movement of the work-webs between the carbons. A connecting piece or guard-plate 42 is set over screws 43 on the blocks, and is held 115 down on the latter by thumb-nuts 44. As shown in the drawings, the carbons 45 are secured at their rear ends to the blades 41, and thence extend forward with the work-webs.

The normal or typing position of the carbon-carrier is that shown in Figure 2. It is thrown to this position and held in this position by means of a coil-spring 46, one end of which bears against a pin 47 on one of the carrier-frame side plates 25, and the other end of which is secured to the rock-shaft 24, to which the arms 23 are fast. For effecting a form-to-form shift of the carbons, rearward along the work-webs, at the 120 125 130

appropriate time, as hereinafter more fully to be explained, the carbon-carrier is thrown from its Figures 1 and 2 position to its Figure 4 position. This throw of the carbon-carrier is effected by means of a bell-crank-lever 48, pivoted at 49, on the left-hand carrier-frame plate 25, and having on the end of its upper arm 50 a handle 51 for operating the same. The lower arm 52 of the bell-crank is slotted at 53 to engage a pin 54 on an arm 55, which forms, with the left-hand carrier-arm 23, a bell-crank. A stop-pin 56 on the ear 33 of the left-hand carrier-frame plate 25 serves as an abutment for the bell-crank, carbon-carrier-operating lever 48, to determine the normal or typing position of the latter, and, through the connections 53 and 54, to determine the normal position in which the carbon-carrier is held by the spring 46.

The work-webs, on passing through the carbon-carrier, in interleavement with the carbons, fall in the form of a loop or slack 57, just forward of the carbon-carrier, and between the latter and a web-supporting table 58; that is to say, when the parts are in the Figure 1 position for typing. In the typing operation, the composite web, gripped by the feed-rolls 14 to the platen, as shown in Figure 1, is given a line-space feed over the table 58, down over the curved forward upper end 59 thereof, down over the paper-table 13 on the platen-carriage, under and around the platen to the printing line, and thence upward across the front of a plate or table 60, and along a staff 61, which is riveted at 62 to the rear of the plate 60, and which carries an adjustable gage 63, to which the leading edges of the work-plies are fed, by forward rotary movement of the platen, to determine the correct position of the web for commencement of typing on a form. It will be noted, Figure 1, that two form-lengths 64 and 65 are shown in advance of the form-length 66, on which typing is to be effected. After positioning the web by means of the leading ends of the form-section 64, such form-section may, however, be severed from the rest of the web by means of a knife-blade 67, as indicated in Figure 1, preliminary to commencement of typing on the form-section 66. As the form-section 66 is line-spaced upward in the typing operation, the slack 57 is taken up. It will be understood, however, that the slack 57 is sufficient not only to permit the web to be advanced from Figure 2 to Figure 1 position, but also to permit completion of typing on the form-section 66, without completely taking up the slack, and, consequently, without pull of the carbons on the blades 41 of the carbon-carrier.

The typing on a form having been completed, the platen is turned in reverse direction by one of the hand-knobs 17 until, as indicated in Figure 2, the carbons 45 are clear of the platen. This position of the web may be indicated by registration of the leading ends of the form-section 65 with a second gage 68, adjustably set on the staff 61.

The next step is to clamp the form-section 65 of the work-webs to the front of the plate 60, so that, as presently to be described, the carbons may be shifted rearward with respect to the work-webs without rearward displacement of the latter. The plate 60 is secured to, and may be unitary with, brackets 69, held by screws 70 to the tops of the side plates 12 of the platen-frame. The plate 60, which is cut away centrally at 71, as indicated in Figure 5, to expose the gage 68, also has its side portions slotted at 72, to receive screws 73, by means of which the knife-blade 67 is adjustably set thereon. It will be understood that the adjustments of the gages 63 and 68 and of the knife-blade 67 are for setting the apparatus for use therein of webs comprised of forms of different lengths.

The brackets 69 have the further function of supporting the device for clamping the work-webs to the plate 60. This device consists of a clamping bar 74, which is provided with a non-slip covering 75, and which is supported on a pair of arms 76 on a rock-shaft 77, journaled in brackets or plates 78, secured to the brackets 69. A spring 79, attached to a pin 80 on the right-hand clamp-bar-arm 76, and to a pin 81 on the right-hand bracket 69, normally holds the clamping bar in Figure 2 position, and returns the same to Figure 2 position when free to do so.

For throwing the bar to the plate 60 to clamp the work-webs, there is pivoted at 82, to the right-hand plate 78, an arm 83 having an operating handle 84 on the end thereof. The other end of the arm 83 is cam-shaped, as indicated at 85, so that, when the arm 83 is thrown forward, the cam 85 acts against the right-hand clamp-bar-arm 76, to force the latter toward the plate 60. The cam 85 is so shaped with respect to the pivot-point 82 that, when the clamp-bar is against the plate 60, the cam is dead-centered with respect to its pivot, thereby permitting the arm 83 to be released, with the clamp 74 nevertheless held in effective position. A stop 86 on the right-hand plate 78 determines the normal position of the clamp-operating arm 83, and another stop 87 on the same plate 78 determines the clamp-locking position of the operating arm 83. The normal position of the clamp-arm 76, and, consequently, of the clamp-bar 74, is determined by engagement of the right-hand clamp-arm 76 with the clamp-operating arm 83 and its cam-shaped end 85, as shown in Figure 2.

In turning back the platen to free the car-

bons therefrom, slack 57 is re-established in the web. In order that the carbons may be smoothly shifted rearward along the web-plies, it is desirable that this slack be eliminated. For this purpose, the table 58, which has a paper-guiding surface of long curvature, is made fast to a rock-shaft 88, journaled in the turned-over upper ends of the brackets 36, so that the table 58 may be 10 swung up from Figure 2 to Figure 3 position. For thus swinging up the table 58, one of the side plates or ribs 89 thereof has attached thereto, at 90, an arm 91 having a handle 92 thereon. This handle is drawn 15 forward, as indicated in Figure 3, to lift the table. A coil-spring 93 on the rock-shaft 88, having one end fast to one of the brackets 36, and the other end made fast to a collar 94 on the rock-shaft, acts to partly 20 counterbalance the weight of the table 58, so as to facilitate the lifting operation. A stop-pin 95 on the right-hand side plate 89 of the table 58, by engagement with an offset 96 (see Figure 3) on an arm 97, forming 25 part of the right-hand side plate 25 of the standard for the carbon-carrier, determines the upper, Figure 3, position of the table 58. It will be noted (see Figure 3) that, when the table 58 is in its upper position, the 30 slack 57 in the web has been eliminated.

The carbon-carrier is now thrown down from Figure 3 to Figure 4 position, in a manner already indicated, by a forward pull on the handle 51; and, in moving downward 35 to Figure 4 position, draws the carbons back a form-length along the work-webs, as indicated in the difference in position of the leading ends of the carbons, observable upon reference to Figures 3 and 4. The curvature of the table 58 being a long one, 40 binding of the carbons on the work-webs does not take place when the carbon-carrier exerts this downward pull on the carbons. For determining the extent of shift of the 45 carbons rearward along the work-plies, the right-hand plate 25 of the carbon-carrier standard has a rearward offset 98, at the end of which are a series of pin-holes 99, into a selected one of which a stop-pin 100, 50 inserted. This pin lies in the path of downward movement of the corresponding carrier-arm 23, and arrests the carbon-carrier after a movement thereof equal to one form-length of the work-webs. Since work- 55 webs of different form-lengths may be used in the machine, the extent of movement of the carbon-carrier may be varied accordingly, by changing the setting of the pin 100 from one to another of the holes 99.

60 After the shift of the carbons has been effected, the handles 51 and 92 are released, so that the table 58 may drop to Figure 2 position by gravity, and the carbon-carrier be thrown up to Figure 2 position by the spring 46. The clamp-locking arm 83 is

then thrown from Figure 3 to Figure 2 position, releasing the work-webs. The platen is now given a forward rotation to bring the leading edges of the leading typed form-section to the gage 63, as indicated in 70 Figure 1; thus positioning the web for commencement of typing on the first untyped form-section, also as indicated in Figure 1; and the leading typed form-section is then severed as hereinbefore indicated. 75

Variations may be resorted to within the scope of the invention, and portions of the improvements may be used without others.

Having thus described my invention, I claim:

1. In a typewriting machine, a revoluble platen, means for holding work-webs, composed of a succession of forms, and carbons interleaved therewith, for line-space feed with the platen, a carrier to which the carbons are anchored at their rear, said carrier being pivoted, means for supporting the composite web in such wise as to provide a slack in the untyped part thereof when the web is in position for commencement of typing of one of its form-lengths, such slack being in front of the carbon-carrier and sufficient to permit of line-feed of the composite web in the typing of a form-section without pull on the carbon-carrier, 90 means for releasing the carbons for shift of the same to an untyped form-section of the work-webs, next succeeding a form-section thereof previously typed, means for drawing upon the web in a crosswise direction, 100 between the platen and the carbon-carrier, to take up the aforesaid slack, and means for moving the carbon-carrier to effect the aforesaid shift of the carbons after such elimination of slack in the web. 105

2. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a table between the carbon-carrier and the platen, over which the web is guided in line-spacing in the typing operation, means for moving the table to take up the slack re-established in the web by the aforesaid retraction of the same, and means for moving the carbon-carrier to shift 110 115 120 125

the carbons along the work-webs to an un-typed form-section thereof, next succeeding the previously-typed form-section thereof, after such elimination of the re-established slack.

3. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a pivotally-mounted table between the carbon-carrier and the platen, over which the web is guided in line-spacing in the typing operation, means for swinging the table on its pivot for taking up the slack re-established in the web by the aforesaid retraction of the same, and means for moving the carbon-carrier to shift the carbons along the work-webs to an untyped form-section thereof, next succeeding the previously-typed form-section thereof, after such elimination of the re-established slack.
4. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a pivotally-mounted table between the carbon-carrier and the platen, over which the web is guided in line-spacing in the typing operation, means for swinging the table upward on its pivot for taking up the slack re-established in the web by the aforesaid retraction of the same, and means for moving the carbon-carrier to shift the carbons along the work-webs to an untyped form-section thereof, next succeeding the previously-typed form-section thereof, after such elimination of the re-established slack, the table having a long curved supporting surface for the webs to provide for free movement of the carbons along the work-webs.
5. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a pivotally-mounted table between the carbon-carrier and the platen, over which the web is guided in line-spacing in the typing operation, means for swinging the table upward on its pivot for taking up the slack re-established in the web by the aforesaid retraction of the same, and means for moving the carbon-carrier to shift the carbons along the work-webs to an untyped form-section thereof, next succeeding the previously-typed form-section thereof, after such elimination of the re-established slack, the table having a long curved supporting surface for the webs to provide for free movement of the carbons along the work-webs, such curved surface extending approximately over the anchorage of the carbons on the carbon-carrier, so that the carbons, without appreciable bending, may be directed from their anchorage tangentially onto the table.
6. In a typewriting machine, a revoluble platen, a platen-frame, a paper-table on the platen-frame at the rear of the platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a pivotally-mounted table between the carbon-carrier and the platen, over which the web is guided in line-spacing in the typing operation, means for swinging the table upward on its pivot for taking up the slack re-established in the web by the aforesaid retraction of the same, and means for moving the carbon-carrier to shift the carbons along the work-webs to an untyped form-section thereof, next succeeding the previously-typed form-section thereof, after such elimination of the re-established slack, the table having a long curved supporting surface for the webs to provide for free movement of the carbons along the work-webs.

- web is guided in line-spacing in the typing operation, means for swinging the table on its pivot for taking up the slack re-established in the web by the aforesaid retraction of the same, and means for moving the carbon-carrier to shift the carbons along the work-webs to an untyped form-section thereof, next succeeding the previously-typed form-section thereof, after such elimination 10 of the re-established slack, the table having a long curved supporting surface for the webs to provide for free movement of the carbons along the work-webs, such curve of the movable web-supporting table being 15 extended to the proximity of the paper-table on the platen-frame, so that the web may be directed tangentially therefrom over the paper-table on the platen-frame to the platen.
- 20 7. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part 25 thereof when the web is in position for commencement of typing of one of its form-lengths, such slack being sufficient to permit of line-feed of the composite web in the typing of a form-section without pull on the carbon-carrier, means whereby the composite web may be retracted to clear the carbons 30 from the platen, after completion of typing on a form, thus re-establishing slack in the web between the carbon-carrier and the platen, a table between the carbon-carrier and the platen, over which the web is guided 35 in line-spacing in the typing operation, and behind which such slack is formed, means for moving the table to take up the slack re-established in the web by the aforesaid retraction of the same, and means for 40 moving the carbon-carrier to shift the carbons along the work-webs to an untyped form-section thereof, next succeeding the previously-typed form-section thereof, after such elimination of the re-established slack.
- 45 8. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part 50 thereof when the web is in position for commencement of typing of one of its form-lengths, such slack being sufficient to permit of line-feed of the composite web in the typing of a form-section without pull on the carbon-carrier, means whereby the composite web may be retracted to clear the carbons 55 from the platen, after completion of typing on a form, thus re-establishing slack in the web between the carbon-carrier and the platen, a table between the carbon-carrier and the platen, over which the web is guided 60 in line-spacing in the typing operation, and behind which such slack is formed, means for moving the table to take up the slack re-established in the web by the aforesaid retraction of the same, and means for moving the carbon-carrier, in such wise as to draw the carbons in a path substantially tangential to the table, to shift the carbons along 65 the work-webs to an untyped form-section thereof, next succeeding the previously-typed form-section thereof, after such elimination of the re-established slack.
- 70 9. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part 75 thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a table between the carbon-carrier and the platen, over which the web is guided 80 in line-spacing in the typing operation, and behind the table, and means for swinging the frame backward, with the carbon-carrier, to effect shift of the carbons to an untyped form-section of the work-webs, next succeeding a form-section thereof previously typed, after the re-established slack has been taken up by the aforesaid movement of the table.
- 85 10. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part 90 thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a table between the carbon-carrier and the platen, over which the web is guided 95 in line-spacing in the typing operation, and behind the table, and means for swinging the frame backward, with the carbon-carrier, to effect shift of the carbons to an untyped form-section of the work-webs, next succeeding a form-section thereof previously typed, after the re-established slack has been taken up by the aforesaid movement of the table.
- 100 11. In a typewriting machine, a revoluble platen, means for holding work-webs, composed of a succession of forms, and carbons interleaved therewith, for line-space feed with the platen, a carrier to which the carbons are anchored at their rear, means for supporting the composite web in such wise as to provide a slack in the untyped part 105 thereof when the web is in position for commencement of typing of one of its form-lengths, such slack being sufficient to permit of line-feed of the composite web in the typing of a form-section without pull on the carbon-carrier, means whereby the composite web may be retracted to clear the carbons from the platen, after completion of typing on a form, thus re-establishing slack in the web between the carbon-carrier and the platen, a table between the carbon-carrier and the platen, over which the web is guided 110 in line-spacing in the typing operation, and behind the table, and means for swinging the frame backward, with the carbon-carrier, to effect shift of the carbons to an untyped form-section of the work-webs, next succeeding a form-section thereof previously typed, after the re-established slack has been taken up by the aforesaid movement of the table.
- 115 12. In a typewriting machine, a revoluble platen, means for holding a multiple-ply web, interleaved with carbons, for line-space feed with the platen, means whereby the composite web may be retracted in the form of a slack behind the platen to free the carbons after typing on the web, a table over which the web is fed to the platen, a carrier to which the carbons are anchored at their rear behind the table, means for moving the table to take up the slack established as aforesaid in the composite web, and means for retracting the carbon-carrier to shift the carbons from a typed to an untyped part of the multiple-ply web after such movement of the table.
- 120 13. In a typewriting machine, a revoluble platen, means for holding a multiple-ply web, interleaved with carbons, for line-space feed with the platen, means whereby the composite web may be retracted in the form of a slack behind the platen to free the carbons after typing on the web, a table over which the web is fed to the platen, a carrier to which the carbons are anchored at their rear behind the table, means for moving the table to take up the slack established as aforesaid in the composite web, and means for retracting the carbon-carrier to shift the carbons from a typed to an untyped part of the multiple-ply web after such movement of the table.
- 125 14. In a typewriting machine, a revoluble platen, means for holding a multiple-ply web, interleaved with carbons, for line-space feed with the platen, means whereby the composite web may be retracted in the form of a slack behind the platen to free the carbons after typing on the web, a table over which the web is fed to the platen, a carrier to which the carbons are anchored at their rear behind the table, means for moving the table to take up the slack established as aforesaid in the composite web, and means for retracting the carbon-carrier to shift the carbons from a typed to an untyped part of the multiple-ply web after such movement of the table.
- 130 15. In a typewriting machine, a revoluble platen, means for holding a multiple-ply web, interleaved with carbons, for line-space feed with the platen, means whereby the composite web may be retracted in the form of a slack behind the platen to free the carbons after typing on the web, a table over which the web is fed to the platen, a carrier to which the carbons are anchored at their rear behind the table, means for moving the table to take up the slack established as aforesaid in the composite web, and means for retracting the carbon-carrier to shift the carbons from a typed to an untyped part of the multiple-ply web after such movement of the table.

ment of the lever causes the bail to be swung down.

19. In a typewriting machine, a revoluble platen, a carriage therefor, means for holding a multiple-ply web, interleaved with carbons, for line-space feed with the platen, means whereby the composite web may be retracted in the form of a slack behind the platen to free the carbons after typing on the web, a table pivotally connected to the platen-carriage, a carrier to which the carbons are anchored at their rear, means for supporting the carrier at a distance rearward of the table, so that the slack in the web may be in the form of a loop between the carbon-carrier and the table, the web passing through the carrier and over the upper portion of the table, and means for swinging the table upward to take up the slack.

20. In a typewriting machine, a revoluble platen, a carriage therefor, means for holding a multiple-ply web, interleaved with carbons, for line-space feed with the platen, means whereby the composite web may be retracted in the form of a slack behind the platen to free the carbons after typing on the web, a table pivotally connected to the platen-carriage, a carrier to which the carbons are anchored at their rear, means for supporting the carrier at a distance rearward of the table, so that the slack in the web may be in the form of a loop between the carbon-carrier and the table, the web passing through the carrier and over the upper portion of the table, means for swinging the table upward to take up the slack, and means for swinging the carbon-carrier downward to shift the carbons rearward along the web-plies after the table has been swung upward.

21. In a typewriting machine, a revoluble platen, a carriage therefor, means for holding a multiple-ply web, interleaved with carbons, for line-space feed with the platen, means whereby the composite web may be retracted in the form of a slack behind the platen to free the carbons after typing on the web, a table depending by its upper end from a pivot on the platen-carriage, a carrier to which the carbons are anchored at their rear, means for supporting the carrier at a distance rearward of the table, so that the slack in the web may be in the form of a loop between the carbon-carrier and the table, the web passing through the carrier and over the upper portion of the table, the carrier-support comprising a bail pivoted below the table-pivot, and means for swinging down the bail to shift the carbons rearward along the web-plies after the table has been swung upward.

22. In a typewriting machine, a revoluble platen, means for holding a multiple-ply web, interleaved with carbons, for line-space feed with the platen, means whereby the

composite web may be retracted in the form of a slack behind the platen to free the carbons after typing on the web, a table over which the web is fed to the platen, a carrier to which the carbons are anchored at their rear behind the table, means for moving the table to take up the slack established as aforesaid in the composite web, means for retracting the carbon-carrier to shift the carbons from a typed to an untyped part of the multiple-ply web after such movement of the table, and adjustable means whereby a variable throw of the carbon-carrier may be determined.

23. In a typewriting machine, a platen, and means at the delivery side of the platen for clamping a work-sheet, comprising a plate over which the work-sheet is set, a clamping piece to be pressed against the plate, an arm on which the clamping piece is supported, a bracket on which the arm is pivoted, and a cam for throwing the arm toward the plate.

24. In a typewriting machine, a platen, and means at the delivery side of the platen for clamping a work-sheet, comprising a plate over which the work-sheet is set, a clamping piece to be pressed against the plate, an arm on which the clamping piece is supported, a bracket on which the arm is pivoted, and a cam for throwing the arm toward the plate, the cam, when in effective position, being dead centered so as to hold the clamp to the plate.

25. In a typewriting machine, a platen, and means at the delivery side of the platen for clamping a work-sheet, comprising a plate over which the work-sheet is set, a clamping piece to be pressed against the plate, an arm on which the clamping piece is supported, a bracket on which the arm is pivoted, a cam for throwing the arm toward the plate, the cam, when in effective position, being dead centered so as to hold the clamp to the plate, and a spring for throwing the clamp-arm from the plate when the clamp-arm is released by the cam.

26. In a typewriting machine, a platen, a platen-frame, brackets on top of the platen-frame, a plate supported by the brackets and against which a work-sheet may be held, a clamping bar for holding the work-sheet against the plate, arms for pivotally supporting the clamping bar on the brackets, a spring for normally holding the clamping bar away from the plate, and a lever pivoted to one of the brackets and carrying a cam for engagement with one of the clamp-bar-supporting arms to force the clamping bar to the plate when the lever is swung.

27. In a typewriting machine, a revoluble platen, a platen-frame, means on the platen-frame on the delivery side of the platen for clamping a multiple-ply web against backward movement, means for rendering the

- clamp normally inoperative, means whereby the multiple-ply web interleaved with carbons may be retracted around the platen until the carbons are free of the platen and a slack is formed in the composite web at the back of the platen, means for throwing the clamp to effective position to engage the leading ends of the multiple-ply web after the same has been thus retracted, a table at the rear of the platen over which the composite web is fed, means for moving such table to take up the slack established as aforesaid in the web, a carbon-carrier rearward of the movable table for anchoring the carbons by their rear ends, and means for moving the carbon-carrier backward to effect a shift of the carbons relative to the multiple-ply web after the table has been moved as aforesaid to take up the slack in the web.
28. In a typewriting machine, a revoluble platen, a platen-frame, means on the platen-frame on the delivery side of the platen for clamping a multiple-ply web against backward movement, means for rendering the clamp normally inoperative, means whereby the multiple-ply web interleaved with carbons may be retracted around the platen until the carbons are free of the platen and a slack is formed in the composite web at the back of the platen, means for throwing the clamp to effective position to engage the leading ends of the multiple-ply web after the same has been thus retracted, a table at the rear of the platen over which the composite web is fed, means for moving such table to take up the slack established as aforesaid in the web, a carbon-carrier rearward of the movable table for anchoring the carbons by their rear ends, and means for moving the carbon-carrier backward to effect a shift of the carbons relative to the multiple-ply web after the table has been moved as aforesaid to take up the slack in the web, the table being of a long curvature with its ends so located with reference to the carbon-carrier and to the platen that, without substantial bending in the web, the web may be directed from the carbon-carrier tangentially to the table and from the table tangentially to the platen.
29. In a typewriting machine, a revoluble platen, a platen-frame, means on the platen-frame on the delivery side of the platen for clamping a multiple-ply web against backward movement, means for rendering the clamp normally inoperative, means whereby the multiple-ply web interleaved with carbons may be retracted around the platen until the carbons are free of the platen and a slack is formed in the composite web at the back of the platen, means for throwing the clamp to effective position to engage the leading ends of the multiple-ply web after the same has been thus retracted, a table at the rear of the platen over which the composite web is fed, means for moving such table to take up the slack established as aforesaid in the web, a carbon-carrier rearward of the movable table for anchoring the carbons by their rear ends, and means for moving the carbon-carrier backward to effect a shift of the carbons relative to the multiple-ply web after the table has been moved as aforesaid to take up the slack in the web, the table being movable upward and the carbon-carrier being movable downward.
30. In a typewriting machine, a revoluble platen, a platen-frame, means on the platen-frame on the delivery side of the platen for clamping a multiple-ply web against backward movement, means for rendering the clamp normally inoperative, means whereby the multiple-ply web interleaved with carbons may be retracted around the platen until the carbons are free of the platen and a slack is formed in the composite web at the back of the platen, means for throwing the clamp to effective position to engage the leading ends of the multiple-ply web after the same has been thus retracted, a table at the rear of the platen over which the composite web is fed, means for moving such table to take up the slack established as aforesaid in the web, a carbon-carrier rearward of the movable table for anchoring the carbons by their rear ends, and means for moving the carbon-carrier backward to effect a shift of the carbons relative to the multiple-ply web after the table has been moved as aforesaid to take up the slack in the web, the table being of a long curvature with its ends so located with reference to the carbon-carrier and to the platen that, without substantial bending in the web, the web may be directed from the carbon-carrier tangentially to the table and from the table tangentially to the platen.
31. In a continuous billing typewriting machine, the combination of a carriage, a platen around which a composite web comprising plies of work-sheets may be fed with interleaved carbon-sheets, a carbon-carrier to which the ends of the carbon-sheets are attached, said carbon-carrier being pivotally supported, and a finger-piece to swing said carbon-carrier away from the platen to free the carbon-sheets from said platen.
32. In a continuous billing typewriting machine, the combination of a carriage, a platen around which a composite web comprising plies of work-sheets may be fed with interleaved carbon-sheets, means pivoted at the rear of said platen to draw the web around the platen to free the carbon-sheets from said platen, a pivoted finger-piece to actuate said carbon-carrier, and a pin-and-slot connection between said carbon-carrier and said finger-piece.
33. In a continuous billing typewriting machine, the combination of a carriage, a platen on said carriage around which a com-

posite web comprising plies of work-sheets may be fed with interleaved carbon-sheets, a carbon-carrier pivoted on said carriage at the rear thereof, a finger-piece to actuate said carbon-carrier, said finger-piece being pivoted on said carriage, and a pin-and-slot connection between said carbon-carrier and said finger-piece.

34. In a continuous billing typewriting machine, the combination of a carriage, a platen around which may be fed a composite web of interleaved work-sheets and carbon-sheets, and means to pull the carbon-sheets backward between the work-sheets when released from the platen, said means comprising a swinging carbon-carrier to which the ends of the carbon-sheets may be attached.

35. In a continuous billing typewriting machine, the combination of a carriage, a platen around which may be fed a composite web of interleaved work-sheets and carbon-sheets, a swinging carbon-carrier, and means to return said carbon-carrier to its normal position after shifting the carbon-sheets backward in the work-sheets, said means comprising a spring, to form a slack loop in the work-web between the platen and the carbon-carrier.

36. In a continuous billing typewriting machine, the combination of a carriage, a platen around which may be fed a composite web of interleaved work-sheets and carbon-sheets, a swinging carbon-carrier, means to feed backward the completed forms, and a gage so located in respect to the leading edges of the work-sheets as to indicate the point at which the carbon-sheets are released from the backward feed.

37. In a continuous billing typewriting machine, the combination of a carriage, a platen around which may be fed a composite web of interleaved work-sheets and carbon-sheets, a swinging carbon-carrier, means to feed backward the completed forms, and an adjustable gage so located in respect to the leading edges of the work-webs as to indicate the point at which the carbon-sheets are released from said backward feed.

38. In a continuous billing typewriting machine, the combination of a carriage

platens around which may be fed a composite web of interleaved work-sheets and carbon-sheets, a swinging carbon-carrier with a spring to return it to its normal forward position, and a pin or stop to limit the backward movement of said carbon-carrier.

39. In a continuous billing typewriting machine, the combination of a carriage, a platen around which may be fed a composite web of interleaved work-sheets and carbon-sheets, a swinging carbon-carrier with a spring to return it to its normal position, and means to adjust the swing of the carbon-carrier to forms of different lengths, said means comprising an adjustable pin or stop to limit the backward movement of said carbon-carrier.

40. In a continuous billing typewriting machine, the combination of a carriage, a platen around which may be fed a composite web of interleaved work-sheets and carbon-sheets, a swinging carbon-carrier, and means to take up the slack in the work-webs to permit the retraction of the carbon-sheets, said means comprising a pivotally mounted table between said platen and carbon-carrier, said table being arranged to swing upwards against the work-web.

41. In a continuous billing typewriting machine, the combination of a carriage, a platen around which may be fed a composite web of interleaved work-sheets and carbon-sheets, a swinging carbon-carrier, and means to advance the work-web from its rolls or folds, said means comprising a table placed between the platen and the carbon-carrier and arranged to swing upwards against the work-webs.

42. In a machine for typing upon a work-web, the combination of a revoluble platen, a carbon-carrier movable rearwardly from a normally forward position behind the platen, the carrier having its carbons interleaved with the plies of the work-web and said carbons shiftable relatively to the web, and a spring for returning the carrier from rearward position to said normally forward position, whereby to form and maintain a loop of loose web between said carrier and the platen.

BURNHAM C. STICKNEY.
